United States Patent [19]

Ho

[11] Patent Number: Des. 314,444

[45] Date of Patent: ** Feb. 5, 1991

[54] HAIR CURLER OR SIMILAR ARTICLE

[75] Inventor: Elizabeth Ho, Kowloon, Hong Kong

[73] Assignee: Windmere Corporation, Miami Lakes, Fla.

[**] Term: 14 Years

[21] Appl. No.: 257,030

[22] Filed: Oct. 12, 1988

[30] Foreign Application Priority Data

Jun. 7, 1988 [GB] United Kingdom 1051334

[52] U.S. Cl. D28/35

[58] Field of Search D28/35, 37, 38; 132/226-236, 263, 269, 271; 219/222, 225

CLAIM

The ornamental design for the hair curler or similar article, as shown and described.

DESCRIPTION

FIG. 1 is a top plan view of a hair curler or similar article, showing my new design;

FIG. 2 is a left side elevational view thereof;

FIG. 3 is a bottom plan view thereof;

FIG. 4 is a right side elevational view thereof;

FIG. 5 is an end elevational view thereof, as seen from the barrel portion; and

FIG. 6 is an end elevational view thereof, as seen from the handle portion.

The fragmentary cord portion is shown for ease of illustration.

FIG. 1

FIG. 2

FIG. 3

FIG. 6
